[57] CLAIM

The ornamental design for a modular vehicle bed liner mat, as shown and described.

DESCRIPTION

FIG. 1 is a top plan view of a modular vehicle bed liner mat showing my new design;

FIG. 2 is a side elevation view thereof looking up from the bottom of FIG. 1;

FIG. 3 is a bottom plan view thereof;

FIG. 4 is a side elevation view thereof looking in from the right of FIG. 1;

FIG. 5 is a greatly enlarged top plan view of the lower left corner thereof shown within the circled region 5 in FIG. 1 illustrating the surface pattern in greater detail; and,

FIG. 6 is a sectional view taken along line 6—6 in FIG. 5.

The pattern which is fragmentarily shown at various locations on the top surface of the design in FIGS. 1, 2, and 4 is understood to be repeated uniformly throughout the top surface thereof and is best illustrated in detail in FIGS. 5 and 6.
